UNITED STATES PATENT OFFICE.

BEN M. HAMLIN, OF CHICAGO, ILLINOIS, ASSIGNOR TO J. V. MEYERING TRUNK COMPANY, OF CHICAGO, ILLINOIS, A CORPORATION OF ILLINOIS.

COMBINED DRAWER-LOCKING DEVICE AND IRONING BOARD FOR WARDROBE TRUNKS.

Application filed July 15, 1920. Serial No. 396,539.

To all whom it may concern:

Be it known that I, BEN M. HAMLIN, a citizen of the United States, and a resident of Chicago, Cook County, and State of Illinois, have invented certain new and useful Improvements in Combined Drawer-Locking Devices and Ironing Boards for Wardrobe Trunks, of which the following is declared to be a full, clear, and exact description.

This invention relates to combined drawer locking devices and ironing boards for wardrobe trunks and its principal object is to provide a unitary structure capable of use as a drawer lock, when in one position, and as an ironing board, when in another position.

As is well known, wardrobe trunks are usually provided with drawers or trays in one section and in some cases, means are provided for locking all of the drawers from one place. Often an ironing board forms part of the wardrobe trunk equipment, and I have provided an ironing board, which is capable of being stored in the drawer section of the trunk when not in use, and so constructed and arranged that it may be attached to said drawer section to extend in front of the drawers to prevent withdrawal and may be locked to said section against removal. The arrangement is such, that part of the attaching means acts as a leg or prop for the ironing board when held in horizontal or ironing position; the drawer section of the trunk may afford the support for the other end of the ironing board.

The invention consists in the several novel features hereinafter fully set forth and claimed.

The invention is clearly illustrated in the drawings accompanying this specification in which:—

Fig. 1 is a perspective view of a wardrobe trunk of ordinary construction equipped with a combined drawer locking device and ironing board embodying a simple form of the present invention; Fig. 2 is a perspective view of the ironing board detached from the trunk; Fig. 3 is a perspective view of a certain combined locking bar and leg or prop for the ironing board and an associated keeper plate; Fig. 4 is a central vertical section taken through the drawer section of

the trunk and showing the device in use as a drawer lock; Fig. 5 is a similar section but showing the device in use as an ironing board, and Fig. 6 is a detail, vertical, fragmental section taken on line 6—6 of Fig. 4.

Referring to said drawings, the reference character 7 designates the hanger or clothes section, and 8 the drawer section of a wardrobe trunk of ordinary and well known construction, these sections being hinged together as usual along vertical edges, and being provided with a trunk lock as is well understood.

In the drawer section 8, are slidably and removably supported a number of drawers or trays 9—10 for receiving articles of apparel, toilet articles or other articles, which it is desired to carry in the trunk.

The combined drawer locking device and ironing board which forms the subject matter of this invention is shown at 11 and comprises in general an ironing board 12 of suitable size and shape and a leg or prop 13 connected at one end to the ironing board, as by a hinge 13^a. Said ironing board may be of sufficient length to extend across all of the drawers, if desired, when held in an upright position and the lower end of the leg or prop 13 as arranged to enter a keeper or apertured plate 14, which is secured to the bottom 15 of the drawer section by screws or rivets 16. If desired the lower end of the leg or prop 13 may be reduced slightly to provide shoulders that may rest on the top of the apertured plate 14 whereby the device may be supported from the bottom of the trunk when in use as a drawer locking device.

On the side of the ironing board adjacent the leg or prop 13 are secured the shanks 17 of two hooks 18 as by screws, rivets or the like, and said hooks are spaced apart sufficiently to receive the leg or prop 13 between them, whereby they act to prevent relative sidewise movement between the ironing board and leg or prop while in drawer locking position. The plate 14 is arranged to hold the ironing board against the drawers when in locking position, and thereby prevent them from being opened.

Secured to the upper end of the ironing board, that is, the end to which the leg or prop is hinged, is a lock 19 which has a

bolt 19^a (preferably spring pressed) that is arranged to enter a keeper plate 20 secured to the underside of the top 21 of the drawer section 8. It will be understood that by placing the leg 13 in the plate 14, and snapping the bolt 19^a of the lock 19 into the keeper plate 20 all of the drawers are locked against withdrawal.

To use the device as an ironing board, the lock 19 is unlocked and the leg 13 detached from the plate 14. The ironing board 12 is then moved into horizontal position, the leg 13 swung down and the hooks 18 engaged with the top drawer 9. Preferably a notch 22 is formed in the front wall 23 of said top drawer 9 through which the hooks 18 may be inserted. By engaging the hooks with the drawer at the notch, the ironing board is thereby held against sidewise movement. The notch also receives the casing of the lock 19 when it is used to lock the ironing board to the top 21. To prevent the top drawer from being pulled out while the device is being used as an ironing board, a separate latch or lock 24 is provided for said top drawer, which has a bolt that engages with a keeper plate 25 secured to the underside of the top 21. The one and the same key may be used for locking or unlocking both locks 19, 24, so that in detaching the device from its drawer locking position, the lock 19 may first be unlocked and then the lock 24 may be locked, thereby preventing outward movement of the top drawer while the device is in use as an ironing board.

I have provided a separate keeper plate 26 on the front of the bottom drawer 10 in position to receive the lower end of the leg or prop 13, when the ironing board is held in horizontal or ironing position. This provides means whereby the ironing board may be wholly supported by the drawer section of the trunk.

To replace the device in drawer locking position, the hooks 18 are detached from the top drawer 9, the leg or prop 13 swung back against the ironing board, inserted in the plate 14, and the ironing board moved back against the drawers bringing the bolt of the lock 19 into locking engagement with the keeper plate 20.

From the above it will be seen that the device may be stored in the drawer section, during transportation without taking up any unnecessary space, and when the trunk is open it locks the drawer. Further, that it may be readily disconnected from the drawer section in its locking position and set up in ironing position.

More or less variation of the exact details of construction is possible without departing from the spirit of this invention; I desire, therefore, not to limit myself to the exact form of the construction shown

and described, but intend, in the following claims, to point out all of the invention disclosed herein.

I claim as new, and desire to secure by Letters Patent:

1. The combination with a wardrobe trunk comprising a drawer section, of a combined drawer locking device and ironing board comprising an ironing board arranged to extend across the drawers, a leg connected thereto, and lock-controlled means for securing said ironing board across the drawers of the drawer section, the trunk and leg acting also to support the ironing board in ironing position. 75

2. The combination with a wardrobe trunk comprising a drawer section, of a combined drawer locking device and ironing board comprising an ironing board arranged to extend across the drawers, a leg connected to said ironing board and removably secured to said drawer section, and a lock for securing said ironing board to said drawer section across the drawers, said drawer section and leg acting also to support said ironing board in ironing position. 85

3. The combination with a wardrobe trunk comprising a drawer section, of a combined drawer locking device and ironing board comprising an ironing board arranged to extend across the drawers, a leg hingedly connected to said ironing board and removably secured to said drawer section, and a lock secured to said ironing board and having a bolt engaging with a keeper on said drawer section, said drawer section also acting to support one end of said ironing board and said leg acting to support the other end of said ironing board in ironing position. 95

4. The combination with a wardrobe trunk comprising a drawer section, of a combined drawer locking device and ironing board comprising an ironing board arranged to extend across the drawers, a leg connected to said ironing board and removably secured to said drawer section, hooks secured to said ironing board, one on each side of said leg and acting to prevent relative sidewise movement between said leg and ironing board, and a lock for locking said ironing board to said drawer section, said hooks being also arranged to engage said drawer section to support one end of the ironing board thereon in ironing position, and said leg acting also to support the other end of the ironing board in ironing position. 110

5. The combination with a wardrobe trunk comprising a drawer section, of a combined drawer locking device and ironing board comprising an ironing board arranged to extend across the drawers, a leg connected to said ironing board and removably secured to said drawer section, a lock 125

- for securing said ironing board to said drawer section, and a hook secured to said ironing board, and arranged to engage said drawer section and support one end of the ironing board thereon in ironing position, said leg acting also to support the other end of the ironing board in ironing position. 5
6. The combination with a wardrobe trunk comprising a drawer section, of a combined drawer locking device and ironing board comprising an ironing board arranged to extend across the drawers, a leg connected to said ironing board and removably secured to said drawer section, a lock 10 for securing said ironing board to said drawer section, and hooks secured to said ironing board, and arranged to engage one of the drawers of said drawer section to support one end of the ironing board there- 15 on in ironing position, said leg acting also to support the other end of the ironing board in ironing position. 20
7. The combination with a wardrobe trunk comprising a drawer section, of a combined drawer locking device and ironing board comprising an ironing board arranged to extend across the drawers, a leg hinged to one end of said ironing board and removably supported on said drawer section, a lock for locking said ironing board to said drawer section, connecting means on said ironing board arranged to engage the uppermost drawer to support one end of the ironing board thereon in ironing position, there being means for securing said uppermost drawer against withdrawal and said leg acting to support the other end of said ironing board in ironing position. 25
8. The combination with a wardrobe trunk comprising a drawer section, of a combined drawer locking device and ironing board comprising an ironing board arranged to extend across the drawers, a leg hinged to one end of said ironing board and removably supported on said drawer section, a lock for locking said ironing board to said drawer section, connecting means on said ironing board arranged to engage the uppermost drawer to support one end of the ironing board thereon in ironing position, there being means for securing said uppermost drawer against withdrawal and said leg acting to support the other end of said ironing board in ironing position. 30
9. The combination with a wardrobe trunk comprising a drawer section, of a combined drawer locking device and ironing board comprising an ironing board arranged to extend across the drawers, a leg hinged to one end of said ironing board and removably supported on said drawer section, a lock for locking said ironing board to said drawer section, connecting means on said ironing board arranged to engage in a notch in the uppermost drawer to support one end of the ironing board thereon in ironing position, there being means for securing said uppermost drawer against withdrawal and said leg acting to support the other end of said ironing board in iron- 35 40 45 50 55 60 65 70 75 80 85 90
10. The combination with a wardrobe trunk comprising a drawer section, of a combined drawer locking device and ironing board comprising an ironing board arranged to extend across the drawers of said drawer section, an ironing board supporting member connected to said ironing board and adapted to detachably engage the trunk, and a lock connection between said ironing board and trunk co-operating with said ironing board supporting member to lock said ironing board across the drawers, said trunk and ironing board support also acting to support the ironing board in iron- 70 75 80 85 90
11. In combination, a wardrobe trunk having a drawer section, and a combined ironing board and drawer locking device comprising a board, means for supporting said board to extend horizontally from the trunk, and means for locking said board to the front of the drawer section of the trunk to thereby lock the drawers in place. 90

BEN M. HAMLIN.
